UNITED STATES PATENT OFFICE

114,699

DESIGN FOR A TOY

Anna Danescu, Detroit, Mich.

Application January 10, 1939, Serial No. 82,268

Term of patent 3½ years

To all whom it may concern:

Be it known that I, Anna Danescu, a citizen of the United States and a resident of 17345 Marx Avenue, in the city of Detroit, county of Wayne, and State of Michigan, have invented a new, original, and ornamental Design for a Toy, of which the following is a specification, reference being had to the accompanying drawing, forming part thereof.

Fig. 1 shows a side elevation of the toy showing my new design.

Fig. 2 shows the same toy as seen at a right angle to the view shown in Fig. 1.

Fig. 3 shows the toy as seen from the bottom.

Fig. 4 shows the toy as seen from the top.

I claim:

The ornamental design for a toy, as shown.

ANNA DANESCU.
